Des. 230,327
Patented Feb. 5, 1974

230,327

LUGGAGE BAG

Claire Cooperstein, 30 E. Hickory St.,
Spring Valley, N.Y. 10977

Filed Jan. 28, 1972, Ser. No. 221,849

Term of patent 14 years

Int. Cl. D3—01

U.S. Cl. D87—5 G

FIG. 1.

FIG. 2.

FIG. 3.

FIG. 4.

FIG. 5.

FIG. 6.

FIG. 7.

FIG. 11.

FIG. 12.

FIG. 13.

FIG. 14.

FIG. 1 is an isometric view of a luggage bag showing my new design;

FIG. 2 is a front elevational view thereof;

FIG. 3 is a side elevational view thereof, as viewed from the right;

FIG. 4 is a rear elevational view thereof;

FIG. 5 is a side elevational view thereof, as viewed from the left;

FIG. 6 is a top plan view thereof;

FIG. 7 is a bottom plan view thereof;

FIG. 8 is an isometric view of a second embodiment of the design of FIG. 1;

FIG. 9 is a front elevational view thereof;

FIG. 10 is a side elevational view thereof, as viewed from the right;

FIG. 11 is a rear elevational view thereof;

FIG. 12 is a side elevational view thereof, as viewed from the left;

FIG. 13 is a top plan view thereof; and

FIG. 14 is a bottom plan view thereof.

I claim:

The ornamental design for a luggage bag, as shown and described.
